Primary Examiner — Michael C Stout*Assistant Examiner* — Fitzgerald L Butac(74) *Attorney, Agent, or Firm* — Wolf, Greenfield & Sacks, P.C.(57) **CLAIM**

The ornamental design for a mixer, as shown and described.

DESCRIPTION

FIG. 1 is a top, front and right side perspective view of a mixer according to our new design;

FIG. 2 is a front elevation view thereof;

FIG. 3 is a rear side elevation view thereof;

FIG. 4 is a left side elevation view thereof;

FIG. 5 is a right elevation view thereof;

FIG. 6 is a top plan view thereof; and,

FIG. 7 is a bottom plan view thereof.

The broken lines illustrate portions of the mixer that form no part of the claimed design.
